[57] **CLAIM**

The ornamental design for a "knob for cookware lid", as shown and described.

DESCRIPTION

FIG. 1 is a perspective view of a knob for cookware lid showing my new design;

FIG. 2 is a top view thereof;

FIG. 3 is a side view thereof;

FIG. 4 is a view of the underside thereof;

FIG. 5 is an opposite side view thereof;

FIG. 6 is view at 90° to side view thereof; and,

FIG. 7 is a view at 270° to side view thereof.

The lid shown in phantom lines depicts the environment of my new design and forms no part of the design of my invention.

1 Claim, 4 Drawing Sheets

FIG. 1

FIG. 2

FIG. 3

FIG. 4**FIG. 5**

FIG. 6**FIG. 7**

UNITED STATES PATENT AND TRADEMARK OFFICE
CERTIFICATE OF CORRECTION

PATENT NO. : Des. 419,372
DATED : January 25, 2000
INVENTOR(S) : Cheng
